YOKE FOR DRAFT-GEAR.

1,356,266.

Specification of Letters Patent. Patented Oct. 19, 1920.

Application filed June 6, 1914. Serial No. 843,345.

To all whom it may concern:

Be it known that we, CHARLES A. CARSCADIN and GEORGE A. WOODMAN, citizens of the United States, both residing at Chicago, in the county of Cook and State of Illinois, have jointly invented certain new and useful Improvements in Yokes for Draft-Gears, of which the following is a specification.

10 Our invention relates in general to railway draft gears and more specifically to a yoke for the same.

Heretofore in draft gears it has been customary to fasten the butt of the draw-bar to the yoke by means of rivets or keys. This connection has proven unsatisfactory for the reason that the rivets and keys are easily broken under the tremendous stress to which the draft gear is customarily subjected in use, thus making necessary frequent repairs.

20 One object of our invention is to provide an improved yoke for draft gears in which the butt of the draw-bar will be held in the yoke without the use of rivets, keys or other fastening means of this nature.

Other objects and advantages of our invention will be apparent as the invention is more fully understood by reference to the 30 following specification when read in connection with the accompanying drawing, in which—

Figure 1 is a perspective view of a draw-bar yoke embodying our invention;

35 Fig. 2 is a side elevation of the yoke and associated parts;

Fig. 3 is a detail view of a draw bar yoke showing means for holding a binder plate; and,

40 Fig. 4 is a cross section of the yoke showing the binder plate in position.

Referring first to Figs. 1 and 2 of the drawings, it will be noted that we have shown a draft gear yoke 10 preferably in the form of a U-shaped member closed at its rear end and provided at its forward end with end flanges 11 which hold the butt 12 of the draw-bar 13 in position when longitudinal stress is exerted thereon. At the 45 forward end of the yoke one side is closed by an integral member 14 and the opposite side is open in order that the draw-bar shank may be moved sidewise into or out of operative position in the yoke. Flanges 50

15 are formed integral with the yoke on the open side thereof and opposite the member 14 and spaced sufficiently apart to allow the shank of the draw-bar to pass sidewise between the same but not sufficiently to allow the butt to be so moved. Mounted in 60 the yoke is a spring 16 having follower blocks 17 at either end to provide a proper bearing for the spring within the yoke.

It will be understood that the enlarged butt of the draw-bar is adapted to fit loosely 65 within the end of the yoke and to be held therein from longitudinal displacement by said usual end flanges or projections, the butt being of such size that when held in normal position against the end flanges it 70 will be held from sidewise displacement by the flanges 15 of the yoke.

It is desirable to provide a binder to strengthen the yoke by holding the top and bottom thereof against spreading and also 75 hold the butt of the draw-bar from sidewise displacement. To this end we have shown in the figures of the drawings means which may be used with our yoke. As shown, the flanges 15 may be so shaped as to form 80 guides 18 in which a plate 19 constructed to engage the guides may be inserted. The guides 18 do not extend to the forward end of the flanges 15, but a portion 20 of said flanges 15 is left as a forward stop for the 85 plate 19, which is inserted from the rear of the flanges 15.

The use of our invention will, it is thought, be clear from the foregoing description. In order to insert the draw-bar 90 within the yoke, the draw-bar is arranged with its butt in the rear of the flanges 15 and is moved sidewise into the yoke, the butt passing behind the flanges 15 and the shank passing between the same. The 95 draw-bar is then moved forwardly until its butt is located between the flanges 15 and side member 14, after which the follower plates and spring are arranged in place in the usual manner. In this position the butt 100 is held from further forward displacement by the end flanges 11 and from sidewise displacement by the side member 14 and side flanges 15.

In using the plate 19 the flanges 15 are 105 formed as shown, or in an equivalent manner, and the plate 19 is inserted with its flanges 21 engaging the guides 18. This

binder plate will prevent the yoke from spreading under stress and in conjunction with the integral side member 14 it provides an especially strong and substantial 5 construction.

It readily will be seen that we have provided a form of yoke for use with railway draft gears which obviates all of the difficulties which are inherent in the yokes of 10 the prior art. No rivets, keys or other fastening means which are liable to be loosened or broken are used in our construction. The butt of the draw-bar is loosely held in position, but in such a way 15 that it is impossible for the draw-bar to become accidentally separated from the yoke.

It is thought that the invention, and many of its attendant advantages, will be 20 understood from the foregoing without any further description, and it will be apparent that various changes may be made in the form, construction and arrangement of the parts without departing from the spirit and 25 scope of the invention, or sacrificing any of its material advantages, the form hereinbefore disclosed being merely a preferred embodiment thereof.

We claim:

30 1. A yoke for railway draft gears comprising a body portion having an opening at one end sufficient only to accommodate the draw-bar shank, flanges integral with said body portion for preventing sidewise 35 displacement of the butt of the draw-bar when said butt is in normal position, said flanges being spaced apart to allow the draw-bar shank to move sidewise between

the same, guides upon said flanges, and binder means adapted to be inserted in said 40 guides for closing the opening between said flanges.

2. A yoke for railway draft gears comprising a body portion having an opening at one end sufficient only to accommodate 45 the draw-bar shank, flanges integral with said body portion for preventing sidewise displacement of the butt of the draw-bar when said butt is in normal position, said flanges being spaced apart to allow the 50 draw-bar shank to move sidewise between the same, guides upon said flanges, and a binder plate adapted to be inserted in said guides for closing the opening between the flanges. 55

3. A yoke for railway draft gears comprising a U-shaped body member, means at the open end of said body member for engaging the butt of the draw-bar, flanged members integral with said body member 60 at its open end adapted to prevent sidewise movement of said butt when in normal position, said flanged members being spaced apart sufficiently to permit the draw-bar shank to pass therebetween, a spring for 65 holding the butt of the draw-bar in normal position against the end of the yoke, guides on said flanged members, and a strengthening plate adapted to be inserted in said guides to close the opening therebetween. 70
